BELT BUCKLE

Filed Nov. 6, 1931

Inventor:
Karl Matheus
By Arnold Schrlich
Atty.

UNITED STATES PATENT OFFICE

KARL MATHEUS, OF CHICAGO, ILLINOIS

BELT BUCKLE

Application filed November 6, 1931. Serial No. 573,481.

This invention relates to expandable buckles and more particularly to belt buckles.

With belts commonly used, the wearer adjusts the same to the shape of his waistline when in an upright position. When bending or in a sitting posture, the shape of a person becomes distorted and the abdomen enlarged, and a belt adjusted for normal size will cause a binding action thereon.

It is, therefore, one of the objects of the present invention to provide a belt buckle, which, when attached to a belt, will provide resilient connection between the ends thereof, and thereby compensate for variations in shape of a wearer due to bending or sitting.

Other objects will appear in the course of the following specification and accompanying drawing in which similar characters represent corresponding parts and in which:

Figure 1 is a perspective view of my improved buckle with a belt attached and locked in position.

Figure 2 is a perspective view of the buckle with parts broken away and shown in section.

Figure 3 is a longitudinal section taken on the line 3-3 of Figure 1.

Figure 4 is a perspective view of the spring box with the spring arranged therein.

Figure 5 is a perspective view of the slide plate and

Figure 6 is a perspective view of the locking bar.

Having reference to the particular embodiment of the invention illustrated 1 indicates a

buckle comprising a spring box 2, having a base 3 concavoconvexly shaped, perforated side walls 4 and end walls 5 and 6. Arranged within the box 2 is an expansion spring 7, having one end 8 in abutment with the wall 5.

Arranged over the spring 7 and between the walls 4 is a slide plate 9, having a depending lip 10 at one end adapted to be inserted between the other end 11 of the spring 7 and the wall 6. Formed at the other end of the

plate 9 is an eye 12 to which is pivotally connected a link 13 by the pin 14. Attached to the link 13 by the clamping buttons 15, at one end 16 is a belt 17.

A cover 18 is arranged upon the box 2 and

has formed thereon depending perforated side walls 19 adapted to straddle the walls 4.

Arranged over the cover 18 is a guide member 20 having a cross piece 21 substantially greater in width than the cover 18, the ends of which are curved inwardly and downwardly to form side walls 22 which are adapted to straddle the side walls 19. The walls 19 are perforated, the perforations at corresponding ends of the walls 4, 19, and 22 adapted to be in alignment and connected together by the cross pins 23 and 24.

The cross piece 21 is adapted to be spaced from the cover 18 whereby the free end 25 of the belt 17 may be inserted therebetween.

Pivottally arranged between the walls 4 in close proximity to their ends 26 is a lock bar 27, comprising a base 28 having perforated side ears 29 adapted to be pivotally connected to the cross pin 24, and end walls 30 and 31, the wall 31 being spaced a greater distance from the center of the perforated ears 29 whereby to overbalance the end 32 of the base 28 so that when the lock bar 27 is in inoperative position the end wall 30 will lie in substantially the same plane as the cover 18 within the cut-out portion 33 thereof.

In use, the belt 17 is slipped around the waist of the wearer and the free end 25 slipped between the cross piece 21 and the cover 18 and drawn until the belt 25 fits snugly when the wearer is in upright position.

The belt 17 is of substantially greater width than the cover 18 so as to conceal the parts under the end 25. When the end 25 is drawn to the desired size, the lock bar 27 is rocked on the pivot 24 whereby the knife edge 34 of the end 30 will grip the underside 35 of the end 25 as shown in Figure 3, the end 31 being in abutment with the underside 36 of the cover 18 thereby limiting further movement of the bar 27 and locking the end 25 in place.

In bending or sitting, pressure will be exerted by the distortion of the wearer's abdomen, against the belt 17 tending to loosen the same. This distortion will cause the end 25 of the belt 17 to be moved outwardly relative to the other end thereof against the tension

of the spring 7. When the normal shape of the abdomen is regained, the spring 7 will expand, thereby drawing the end 25 inwardly. When it is desired to release the 6 end 25 from locked position, the end 25 is drawn inwardly to tighten the belt, thereby rocking the bar 27 on its pivot 24 to bring the end 30 in the plane of the cover 18. The end 25 is then drawn outwardly to remove the 10 same from the buckle 1.

From the foregoing, it will be seen that I have invented a simple and efficient device which will be economical to manufacture and it is to be understood that various changes 15 may be made in the details of construction without departing from the spirit of the invention or the appended claims.

Having thus described my invention, what I claim is:—

20 1. A buckle comprising a concavoconvex base, said base having side and end walls adapted to form a chamber, an expansion spring arranged in said chamber, a slide plate arranged above said chamber and having a depending lip adapted to engage one end of said spring, said side walls extending beyond said end walls and having aligned perforations in their corresponding ends, a cover having depending side walls adapted 25 to a straddle the side walls of said base and having perforated ends adapted to align with the corresponding ends of said first mentioned side walls, a guide member comprising a cross plate spaced from said cover and having depending side walls adapted to straddle said cover side walls and having perforated ends adapted to align with the corresponding perforated ends of said cover side walls, cross pins adapted to be inserted 30 through the corresponding ends of said base, cover, and guide whereby to connect the same together, means for connecting the other end of said slide plate to one end of a belt, and means pivotally carried by one of said cross 35 pins and adapted to releasably connect the free end of a belt to said buckle.

2. A buckle comprising a concavoconvex base, said base having side and end walls adapted to form a chamber, an expansion 40 spring arranged in said chamber and having one end adapted to abut one of said end walls, a slide plate adapted to close said chamber and having a depending lip adapted to engage the other end of said spring, said side walls having aligned perforations in their 45 corresponding ends, a cover having depending side walls having perforations adapted to align with the perforations in said first mentioned side walls, a guide member comprising a cross plate of greater width than said cover and spaced therefrom, and having depending perforated side walls adapted to straddle said cover, said perforated ends adapted to align with corresponding perforated side walls of said cover, cross pins

adapted to connect the corresponding side walls of said base, cover, and guide, a lock bar pivotally carried by one of said cross pins and adapted to lock the free end of a belt in adjusted positions to said buckle, and 70 means whereby the other end of a belt may be connected to the other end of said slide plate.

In witness whereof, I have hereunto set my hand and seal this 14th day of October, 75 A. D. 1931.

KARL MATHEUS.
